SHELL CANE

Ruth R. Dumbleton, Madison, Wis.

Substituted for abandoned application Serial No.
507,513, December 18, 1943. This application
November 15, 1944, Serial No. 563,508

5 Claims. (Cl. 135—45)

This invention relates to new and useful improvements in a shell cane.

This is a refile of my original application filed on December 18, 1943, Serial Number 507,513.

More specifically, the invention proposes the construction of a shell cane characterized by a rod-like staff portion formed of a plurality of axially aligned discharged or empty thirty or thirty-five calibre shell cases into the front end of which dummy points have been mounted in a manner to permit the front end of the shell cases to be engaged in and rigidly connected with openings formed in the back ends of the shell cases to form the rod-like staff.

Still further it is proposed to provide the top of the rod-like staff with a handle formed from a pair of shell cases rigidly connected together and in turn rigidly mounted in position on the topmost shell case of the rod-like staff in a manner to complete the shell cane.

Still another object of this invention proposes the provision of a means for releasably connecting together the shell cases of the rod-like staff in a manner to permit some of the shell cases to be added thereto in a manner to adjust the length of the shell cane.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a elevational view of a shell cane constructed in accordance with this invention.

Fig. 2 is a partial enlarged vertical sectional view taken substantially on the line 2—2 of Fig. 1.

Fig. 3 is a view similar to Fig. 1 but illustrating a modification of the invention.

Fig. 4 is an enlarged horizontal sectional view taken on the line 4—4 of Fig. 3.

Fig. 5 is an enlarged partial vertical sectional view taken on the line 5—5 of Fig. 3.

Fig. 6 is a partial vertical sectional view taken on the line 6—6 of Fig. 5.

The shell cane, according to this invention, is preferably constructed of a plurality of axially aligned empty shell cases 10. These shell cases are of the thirty or thirty-five calibre type and have dummy points 11 mounted in the front end thereof. The back end of each of the shell cases 11 is provided with an opening 12. The opening 12 is of a diameter corresponding to the diameter of the dummy points 11 so that these points may

be engaged into the openings 12 until the front end of the next adjacent shell case 10 strikes the back end of the shell case into which the point 11 was inserted. The adjacent ends of the 5 shell cases are then welded together at 13 (see Fig. 2) to connect these shell cases securely together and form an elongated rod-like staff 14.

A handle 15 is mounted on the top end of the rod-like staff 14. This handle 15 is formed of a 10 pair of adjacent shell cases 10 which are welded together and in turn welded to the topmost shell case 10 of the rod-like staff 14.

The shell cane will then appear as shown in Fig. 1, and it may, if desired, be embellished or 15 ornamented throughout its length in any desired manner to add to the decorative appearance thereof. A feature of the invention resides in the fact that it makes use of the empty thirty and thirty-five calibre shell cases which will be 20 collected by the army during the present war and for which there will be very little value at the close of the war.

In the modification of the invention shown in 25 Figs. 3—6 a construction is illustrated wherein the shell cases 10 are removably connected together to permit some of the cases to be removed or others to be added for the purpose of increasing the length of the cane.

In this form of the invention each of the 30 dummy points 11 mounted within the shell cases 10 is provided with a radially extending pin 17 which is adapted to be passed through a radial auxiliary opening 18 which extends from the side of the opening 12 cut in the back end of the shell case 10. This will cause the pins 17 to be disposed within the shell cases 10 to be releasably 35 engaged into a complementary cutout 19 formed in a metallic block 20 mounted within the back end of each of the shell cases 10. The cutout 40 19 is of such design as to require that the pins 17 be snapped into position within these openings so that the block 20 will act to securely grip the pins 17 and maintain the shell cases rigidly connected. However, it is possible to twist adjacent shell cases in opposite directions to cause the pins 17 to be disengaged from the cutouts 45 19, freeing the pins so that the shell cases may be separated as desired.

In other respects this form of the invention 50 is identical to the previous form and like parts are indicated by like reference numerals.

While I have illustrated and described the preferred embodiments of my invention, it is to be understood that I do not limit myself to the 55 precise constructions herein disclosed and the

right is reserved to all changes and modifications coming within the scope of the invention as defined in the appended claims.

Having thus described my invention, what I claim as new, and desire to secure by United States Letters Patent is:

1. A shell cane, comprising a plurality of empty shell cases having openings in their respective back ends, said cases being axially aligned in the same direction and their front ends severally engaging and rigidly mounted in adjacent openings forming a rod-like staff, and a handle mounted on the top of said rod-like staff.

2. A shell cane, comprising a plurality of empty shell cases having openings in their respective back ends, said cases being axially aligned in the same direction and their front ends severally engaging and rigidly mounted in adjacent openings forming a rod-like staff, and a handle mounted on the top of said rod-like staff, said shell cases having dummy points mounted in the respective front ends thereof and said openings being of a diameter corresponding to the diameter of said points, the projected end of the respective points being inserted into the adjacent openings and the front ends of the shell cases, each contacting the back end of the next adjacent case.

3. A shell cane, comprising a plurality of empty shell cases having openings in their respective back ends, said cases being axially aligned in the same direction and their front ends severally engaging and rigidly mounted in adjacent openings forming a rod-like staff, and a handle mounted on the top of said rod-like staff, said shell cases having dummy points mounted in the respective front ends thereof and said openings being of a diameter corresponding to the diameter of said points, the projected end

of the respective points being inserted into the adjacent openings and the front ends of the shell cases, each contacting the back end of the next adjacent case, and said adjacent shell cases having their adjacent ends fixed together.

4. A shell cane, comprising a plurality of empty shell cases having openings in their respective back ends, said cases being axially aligned in the same direction and their respective front ends severally engaging and rigidly mounted in adjacent openings forming a rod-like staff, and a handle mounted on the top of said rod-like staff, said shell cases having dummy points mounted in the respective front ends thereof and said openings being of a diameter corresponding to the diameter of said points, the projected end of the respective points being inserted into the adjacent openings forming a rod-like staff, and a handle mounted on the top of said rod-like staff, said shell cases having dummy points mounted in the respective front ends thereof and said openings being of a diameter corresponding to the diameter of said points, the projected end of the respective points being inserted into the respective openings and the front ends of the shell cases, each contacting the back end of the next adjacent case, a block mounted within each shell case at a point adjacent the dummy point of the next adjacent shell case which is inserted into the opening and said block being formed with a cutout, and pins extending from said respective dummy points within said shell cases and releasably engageable with said cutouts for releasably connecting said shell cases together.

5. A shell cane, comprising a plurality of empty shell cases having openings in their respective back ends, said cases being axially aligned in the same direction and their front ends severally engaging and rigidly mounted in adjacent openings forming a rod-like staff, and a handle mounted on the top of said rod-like staff, said handle comprising adjacent shell cases secured together and mounted in position on said rod-like staff.

RUTH R. DUMBLETON.
